CENTRIFUGAL FAN

Kenton D. McMahan, Schenectady, N. Y., assignor to General Electric Company, a corporation of New York

Application October 26, 1939, Serial No. 301,416

5 Claims. (Cl. 230—117)

The present invention relates to centrifugal fans and similar devices having rotatable parts which must be accurately aligned with a cooperating part or device.

The object of my invention is to provide an improved construction and arrangement for resiliently supporting and aligning a rotatable device and in particular for resiliently supporting and aligning centrifugal fan impellers with respect to the fan casings. For a consideration of what I believe novel and my invention, attention is directed to the following description and the claims appended thereto.

In the accompanying drawing, Fig. 1 is a sectional elevation of a centrifugal fan embodying my invention; Fig. 2 is a fragmentary perspective view of one of the resilient supporting rings; Fig. 3 is an enlarged sectional view of the resilient support; and Fig. 4 is a diagrammatic view illustrating the use of the fan.

Referring to the drawing, there is shown a centrifugal fan having a scroll casing 1 provided with an inlet orifice ring 2 connected to a duct 3, and a discharge outlet 4 connected to a duct 5. The fan casing is supported on a base 6 having a pedestal 7 at the front bolted to the fan casing and having a pedestal 8 at the rear provided at its upper end with a cylindrical housing 9 for an electric motor 10. At the ends of the housing 9 are circular end frames 11 and 12 which are clamped to the ends of the housing 9 by through-bolts 13 extending through clearance openings (not shown) in the motor. The end frame 11 forms part of the rear wall of the fan casing. By turning the fan casing with respect to the pedestal 7 and the end frame 11, the angular position of the discharge outlet 4 may be changed to conform with the position of the duct 5. Within the fan casing is a bladed centrifugal fan impeller 14 having a hub 15 fixed to the motor shaft 16. The end of the motor shaft is covered by a cap 17 fixed to the impeller hub. The front ends 18 of the fan blades project within the inlet orifice 2 and serve as scoops for directing air from the inlet to the discharge edges 19 of the fan blades. A shroud ring 20 secured to the blades at the front ends assists in directing the air. Leakage of air between the fan blades and the inlet opening is prevented by a flange 21 on the shroud ring which has a running clearance with a flange 22 at the inner end of the casing inlet 2. Leakage at the back of the fan is prevented by a cylindrical flange 26 on the impeller hub 15 and projecting within a flange 27 on the end frame member 11. The flanges 26 and 27 are closely spaced and cooperate to provide a seal. For best operation of the centrifugal fan it is desirable that the clearance between the flanges 21 and 22 and between the flanges 26 and 27 be a minimum.

The motor and impeller are resiliently supported by resilient rings 28 of rubber or similar material arranged within circular openings in the end frames 11 and 12 and surrounding hubs 29 at each end of the motor. The outer surfaces 30 of the rubber rings are of slightly smaller diameter than the concave inner surfaces 31 of the openings in the end frames 11 and 12. The rubber rings 28 may therefore be easily inserted in the openings in the end frames. The rubber rings are clamped to the motor hubs 29 by clamping rings 32 secured to the motor hubs by bolts 33 extending through axial grooves 34 in the inner surfaces of the rubber rings. The bolts cooperate with the grooves to non-rotatably key the rubber rings to the motor hubs. Before the bolts 33 are tightened, the rubber rings fit loosely between the concave surfaces 31 on the end frames 11 and 12 and between the opposed radial surfaces 35 and 36 respectively on the motor hubs and on the clamping rings and concentric with the surfaces 31. When the bolts 33 are tightened, the rubber rings are compressed axially and the rubber flows or is squeezed radially, being forced outward into tight engagement with the concave surfaces 31 and being forced laterally into tight engagement with the surfaces of 35 and 36 on the motor hub and clamping ring.

Due to the grooves 37a in the inner surface 30 of the rubber rings and also to the fact that the pressure of the clamping rings is mainly on the inner part of the rubber rings, the rubber rings are squeezed mainly outward so that pressure is not exerted on the bolts 33 in an amount great enough to prevent turning of the bolts. From one aspect, the rubber rings are subjected to an eccentric squeezing. When the rubber rings are squeezed between the clamping rings, the rubber rings are non-rotatably secured by friction to the concave surfaces 31 and to the radial surfaces 35 and 36. The axial grooves 34 are therefore unnecessary in so far as the securing of the rubber rings to the motor hubs is concerned. Since the rubber rings are fixed both to the motor hubs 29 and to the end frames 11 and 12, the rings provide a torsionally resilient support for the motor and impeller spaced apart along and surrounding the axis of the motor which decreases the noise and vibration transmitted from the motor and impeller.

Since the weight of the motor and impeller is carried by the lower half of the rubber rings, the compression of the rubber rings will vary with the position in which the fan is mounted. For example, if the fan is mounted on the floor, as shown in full lines in Fig. 4, the weight of the motor and impeller will be carried by the lower half of the rubber rings. If the motor is suspended from the ceiling, as shown in dotted lines in Fig. 4, the weight will now be carried by that

part of the rubber rings which was the upper half when the fan was mounted on the floor. The compression of the rubber rings under the weight of the motor and impeller causes the axis of the impeller to be shifted with respect to the fan casing. This obviously changes, the running clearance between the impeller and casing and makes necessary either the provision of larger clearance, resulting in less efficient operation, or the use of 10 expensive constructions for re-aligning the impeller with the casing. Alignment of the impeller with the casing is also necessary to take care of variations in the casing dimensions which are likely to be large if the casing is made of sheet metal. The variations in casing dimensions may be due to 15 manufacture or to distortion of the casing during use.

In the present construction the alignment of the impeller with the casing is effected by varying the compression of the rubber rings between the clamping rings 32 and the motor hubs 29. The function of the clamping rings in aligning the impeller is illustrated in Fig. 3. At the lower half of Fig. 3 the bolts 33 are tighter than at the upper half, and accordingly the rubber rings are 20 squeezed radially outward to a greater extent at the lower half. If no load were carried by the rubber rings, the distance A would therefore be greater than the distance B and the center of the motor shaft and impeller would be above the center of the fan casing. When the support is arranged so that the load is carried on the lower half of the rubber rings, the rubber deflects so 25 that the distance A becomes equal to the distance B and, in other words, brings the center of the motor and impeller into coincidence with the center of the fan casing. By tightening or loosening the bolts 33 around the circumference of the clamping rings 32 it is therefore possible to align the motor and impeller with respect to the fan 30 casing.

In carrying out the alignment operation, the impeller 14 is removed from the motor hub and the bolts 33 in the clamping ring 32 at the end frame 11 are adjusted so that the motor shaft 16 is centrally located with respect to the casing flange 21. The impeller 14 is then mounted on the motor shaft and the bolts in the clamping ring at the end frame 12 are adjusted to provide the proper clearance between the flanges 21 and 22. When this operation is completed the impeller is accurately aligned with respect to the 35 fan casing for the position in which the fan is to be mounted. If the fan is moved to another position the alignment operation will have to be 40 repeated since the load distribution on the rubber rings is changed by the new location.

The above-described construction provides an efficient resilient mounting which has the further advantage of facilitating alignment of the impeller with its casing. Although the invention has been described as applied to a centrifugal fan it is applicable to other uses where a device mounted on a shaft is to be resiliently supported and aligned with a cooperating part.

What I claim as new and desire to secure by Letters Patent of the United States is:

1. In combination, a motor, an impeller mounted thereon, a support, a casing for the impeller with which the impeller has a running clearance, inner and outer surfaces on the motor and support spaced apart along and surrounding the motor axis, a resilient mounting for supporting

the motor for yielding movement relative to the casing comprising rings of rubber-like material between said surfaces, and means for compressing the rings axially to squeeze the rings radially into engagement with said surfaces, said compressing means being adjustable to vary the compression of the rings around the circumference thereof to displace the motor axis radially and thereby align the impeller with its casing.

2. In combination, a motor, an impeller mounted thereon, a support, a casing for the impeller with which the impeller has a running clearance, a resilient mounting for supporting the motor for yielding movement relative to the casing comprising members of rubber-like material spaced along and surrounding the motor axis, inner and outer surfaces on the motor and support engageable by the inner and outer surfaces of said members, and means for compressing said members axially to squeeze the members radially into engagement with said surfaces, said compressing means adjustable to vary the compression of said members around the motor axis to displace the motor axis radially and thereby align the impeller with its casing.

3. In combination, a motor, an impeller mounted thereon, a support, a casing for the impeller with which the impeller has a running clearance, a resilient mounting for supporting the motor for yielding movement relative to the casing including a ring of rubber-like material surrounding the motor axis, concentric inner and outer surfaces on the motor and support, and clamping means for compressing said rubber ring axially to squeeze the rubber ring radially into engagement with said surfaces, the pressure of said clamping means being adjustable around the motor axis whereby the amount of radial squeezing of the rubber ring is adjustable to shift the motor axis radially and align the impeller with its casing.

4. In combination, a structure having a shaft journaled therein, a support, said structure and said support comprising members movable relative to each other transverse to the axis of the shaft, a resilient mounting for said structure including a ring of rubber-like material surrounding the axis of the shaft and having inner and outer surfaces, one of said surfaces having a circumferential groove therein and the other of said surfaces engaging one of said members, clamping means secured to the other of said members and engaging the ends of the ring for compressing the ring axially adjacent said groove whereby said other surface of the ring is squeezed radially into engagement with said one member.

5. In combination, a structure having a shaft journaled therein, a support, a part with which the shaft is to be aligned, said structure and said support comprising members movable relative to each other transverse to the axis of the shaft, a resilient mounting for supporting the structure for yielding movement relative to said part comprising rubber-like material surrounding the axis of the shaft and having inner and outer surfaces engaging said members, and means for compressing said rubber-like material axially to squeeze it radially and thereby shift the axis of said shaft relative to said support, said compressing means being adjustable around the axis of the shaft to vary the amount of radial squeezing whereby the shaft may be aligned with said part.

KENTON D. McMAHAN.
